UNITED STATES PATENT OFFICE.

WALTER S. TOWER AND PETER D. CAMPHUIS, OF WALLACE, IDAHO.

JIG.

1,159,295.

Specification of Letters Patent.

Patented Nov. 2, 1915.

Application filed July 28, 1914. Serial No. 853,613.

To all whom it may concern:

Be it known that we, WALTER S. TOWER, a citizen of the United States, and a resident of Wallace, in the county of Shoshone and State of Idaho and PETER D. CAMPHUIS, a citizen of the United States, and a resident of Wallace, in the county of Shoshone and State of Idaho, have invented certain new and useful Improvements in Jigs, of which

10 the following is a specification.

This invention relates to ore jigs, and the main object thereof is to provide means for moving such a device in a substantially elliptical path and to adjust the inclination 15 of the ellipse at will, with a consequent effect on the direction and speed of movement of ore in the jig; a further object is to direct the ore not concentrated through the bottom screen of the jig into suitable cups in such 20 manner as to leave the tailings outside of said cups, the ore containing basket being movable within a tank containing water maintained at a level above the ore level.

The invention is fully described in the following specification, of which the accompanying drawings form a part, in which the separate parts are designated by the same reference characters in each of the views, and in which:

30 Figure 1 is a side elevation of the invention, partly in section on the line 1—1 of Fig. 2; Fig. 2 is a plan view thereof; Fig. 3 is a section taken on the line 3—3 of Fig. 1; Fig. 4 is an enlarged sectional view of a detail, taken on the line 4—4 of Fig. 5; and Fig. 5 is a similar view taken on the line 5—5 of Fig. 4.

In the drawings forming a part of this application we have shown a tank 6, adapted 40 to contain water, provided with transverse plates 7, and having four brackets 8, two of which are mounted upon each of two supporting plates 9 above and adjacent the ends of the tank; pivot blocks 10 are supported 45 at the tops of said brackets and serving as supports for springs 11 having, each, a washer 12 at the top thereof to carry a rod 13 vertically movable in the corresponding pivot block and in pivotal connection with 50 a shaft 14 pivoted to brackets 15, beneath each of the plates 9, secured to a basket 16

having the open bottom thereof covered by a screen 17, as clearly shown in Figs. 1 and 3, and it will be seen that the springs 11 support the basket 16 but in such manner as to 55 permit vertical movement thereof, whereas the pivot blocks 10 permit horizontal movement thereof.

The basket 16 is provided, above the screen 17, with a plurality of transverse 60 plates 18 and with inclined plates 19, of somewhat greater height than the plates 18, leading to corresponding cups 20 having an opening in the lower portion thereof between the inner ends of each pair of plates 65 19, as shown at 21, Figs. 1 and 4, a gate 22 being vertically adjustable on each cup to control the corresponding opening 21 and held in position by means of a spring 23 and bolt 24, tensionally, and each cup is also provided with a transverse plate 25 provided with an opening 26 intermediate the height thereof controlled by a gate 27 having two openings 28 and 29 therein and tensionally 70 held by means of a spring 30 and bolt 31, 75 and it will be seen that the height of the opening through the partition so formed may be regulated, from the screen 17, as may also the size of the opening.

The screen 17 is held in place by means 80 of a plurality of longitudinally arranged beams 32 in turn held by brackets 33, Fig. 3, secured to transverse beams 34 secured to the lower side of the side members of the basket, and the basket is also provided with 85 a transverse, centrally arranged, plate 35 secured to the tops of the side members, Fig. 3, by means of bolts 36, bolts being also provided for holding bearings 37 for a stub-shaft 38, Figs. 1 and 3. 90

Mounted upon the side members of the tank 6 are two frame members 39 serving as bearings for a shaft 40 extending across the tank and provided with a fly-wheel 41 at one end, and two pulleys 42 and 43, one of 95 which is tight and the other loose, at the other end, and said shaft also carries an eccentric disk 44, centrally thereof, having a band 45 thereon from which depends a pitman 46 provided with teeth 47 and connected with the stub-shaft 38, and it will 100 be seen that rotation of the power shaft 40

moves the basket 16 up and down, this being permitted because of the coil springs 11.

Vertically adjustable on the pitman 46 is a block 48 having teeth 49 for engagement with the teeth 47, and being locked in position by means of bolts 50, Fig. 1, and said block carries a stub-shaft 51, Fig. 3, upon which is mounted a yoke-shaped link 52 and the other ends of which are mounted upon a shaft 53 carried by two oppositely disposed rock-bars 54 pivoted to the frame members 39 at 55 and provided with segmental arms 56 having, each, a slot 57 therein, and through which passes a bolt 58 whereby said rock-bars may be locked in adjusted position to a portion 58^a of the said frame members.

It will be seen that, if the block 48 be vertically adjusted on the pitman 46, the horizontal throw of the pitman is changed accordingly, this also being true if the rock-bars are vertically adjusted, and doubly so if each be oppositely adjusted, although they may be adjusted to insure an elliptical path of movement of the block 48 the major axis of which is perpendicular to the tank, but we desire to so adjust these parts as to insure an inclined position of the major axis, whereby an inclined, elliptical, path of movement of the basket 16 results, preferably at such inclination as to insure the movement of the ore in the basket toward the left hand end of the same, whereby the ore is directed toward corresponding cups by the pairs of inclined plates 19.

Secured to each of the frame members 39 is a bearing 59 for a shaft 60 carrying a handle-bar 61 and an arm 62 pivoted to a link 63 in turn mounted on the shaft 53, and it will be seen that, if the bolts 58 be loosened, the rock-bars may be raised or lowered by means of the handle-bar 61 and held in a desired position until the bolts are again tightened.

It will thus be seen that we swing the ore basket in the path of an adjustable ellipse, to correspondingly effect the movement of the ore in the basket; that a portion of the ore is precipitated through the screen 17; that the remaining ore is carried toward and into cups through adjustable openings according to the character of the ore, with the tailings on the top of the body of ore not entering said cups, this being accomplished in water at a suitable depth, preferably at a water level six inches above the ore level; and that the inclined adjustment of the elliptical path of the basket may be such as to accommodate the jig to ores of different classes or character.

The purpose of the inclined plates 19 is to draw the ore from the sides of the basket after concentration, and to enable us to secure different depths of bedding. This particular jig is designed to run with a two and one-half inch bedding of ore. If it becomes

necessary, on account of the different grades of ore, to change the depth of the bedding, the front gate of the cup is partially closed, causing the ore to pass through more slowly, thus banking the ore up to a greater depth over the jig in the corresponding compartment, or, the gate is opened to cause a lighter bedding in such compartment. After the desired jig motion is adjusted, the cups must be adjusted to give the proper depth of bedding and grade of ore desired. To concentrate many different grades of ore as we do by changing the motion of the jig, it is necessary to have this means for controlling the depth of the bedding, and the desired results could not be obtained by the jig motion alone, nor by the adjustment of the cup gates, as a complemental adjustment of the cup gates is essential to a certain adjustment of the path of the jig, and the path of the jig is changed to accommodate the device to the different grades and characters of ores.

We prefer to make the frame members 39 and the spring basket hangers slidable along the length of the tank and the basket in order to accommodate the jig to different sizes and weights of ores, and we reserve the right to make such other changes in and modifications of the details of construction herein shown and described, within the scope of the following claims, as do not depart from the spirit of the invention or sacrifice its advantages.

Having fully described the invention, what we claim as new, and desire to secure by Letters Patent, is:—

1. An ore jig, comprising a tank, a jig screen therein, means for oscillating the same, a plurality of spaced plates arranged transversely therein to retain ore therebetween to form a bed of ore, a cup in said screen consisting of a casing open at top and bottom and having an opening in the lower part of the front thereof, an adjustable gate for controlling the height of the upper edge of said opening, a partition in said cup arranged transversely thereof and provided with an opening intermediate the height thereof, an adjustable gate for controlling the height of the lower edge of said partition opening, and diagonally inclined overflow plates of greater height than said transverse plates leading from the walls of said screen to said cup to direct ore to the opening in the front thereof.

2. An ore jig, comprising a tank adapted to contain a liquid, a basket therein provided with a screen in the bottom thereof and adapted to receive ore, spring hangers on said tank in pivotal connection with said basket, a shaft, an eccentric disk thereon in operative connection with said basket, means for rotating said shaft, a pitman rod connecting said disk and basket, a block adjustable on said pitman rod, a rock-bar adjust-

ably mounted on said tank, a shaft carried thereby, and a link connecting said block and rock-bar to impart horizontal movement to said basket in the actuation thereof by 5 said eccentric disk, the adjustment of said block and said rock-bar serving to change the direction of basket movement.

In testimony whereof we have signed our

names to this specification in the presence of the subscribing witnesses.

WALTER S. TOWER.
PETER D. CAMPHUIS.
